UNITED STATES PATENT OFFICE.

CHARLES E. SCRIBNER, OF JERICHO, VERMONT, ASSIGNOR, BY MESNE ASSIGNMENTS,
TO WESTERN ELECTRIC COMPANY, INCORPORATED, A CORPORATION OF NEW YORK.

SYNCHRONIZING SYSTEM.

1,276,581.

Specification of Letters Patent. Patented Aug. 20, 1918.

Application filed May 19, 1915. Serial No. 29,119.

To all whom it may concern:

Be it known that I, CHARLES E. SCRIBNER, a citizen of the United States, residing at Jericho, in the county of Chittenden and State of Vermont, have invented certain new and useful Improvements in Synchronizing Systems, of which the following is a full, clear, concise, and exact description.

This invention relates to synchronizing systems, and its principal object is to provide improved means for insuring the maintenance of a synchronism between separated rotatable bodies operatively interconnected by a transmission line.

In accordance with its general features, the invention contemplates a system of the above type in which at least one of the bodies is motor driven, and wherein the magnetic field of this motor may be shifted under the control of line current impulses to affect the speed thereof. More specifically, the invention comprises a system and apparatus wherein the motor driving the body whose speed is to be corrected, is provided with a plurality of groups of operating windings. The energization of these groups of windings is controlled by a multiple switch affected through the influence of line current impulses to shift the magnetic field as required.

The above and other objects of this invention will be fully set forth in the following description and claims, and will be more readily understood by reference to the accompanying drawings in which Figures 1 and 2 combined show the system of connections and the operative mechanism diagrammatically.

A transmitting current distributor 5, provided with a rotatable brush carrying arm 6, is adapted in the usual manner of multiplex telegraphs to impart signaling and synchronizing current impulses to a transmission line L. At the receiving station, these impulses pass through the windings of a polarized line relay 10 of the usual construction and, if duplex operation is desired, the usual artificial line AL is provided.

At the station in which the line relay 10 is located, there is also provided a current distributor constructed, in the usual manner, of insulated transmitting, receiving and correcting segments and the necessary common conducting rings. These segments and their

corresponding rings are shown partly developed in the lower right-hand corner of Fig. 1, and are adapted to be interconnected by suitable brushes 11 which are rotated in the direction of the arrow of Fig. 2 by a phonic motor whose construction will be hereinafter described.

The point between the windings of line relay 10 is connected in a well-known manner to the common transmitting or sending ring of the distributor, and the relay is provided with an armature 12 connected to a grounded source of energy 13 and coöperating with a pair of contacts 14 and 15. Contacts 14 and 15 are respectively connected through suitable resistances 16 and 17 to a pair of windings 18 and 19 of a polarized leak relay 20. The point between windings 18 and 19 is grounded, as shown. Leak relay 20 is equipped with an armature 25 which is connected to the common correcting ring of the distributor and coöperates with a contact 26 connected to the conductor between contact 14 and resistance 16. Contact 14 is also connected to the common receiving ring of the distributor in the usual manner.

There is also provided a polarized correcting relay 30 provided with a pair of windings 31 and 32, two terminals of which are connected together and grounded. The other terminal of winding 32 is connected to the conductor interconnecting resistance 17 and contact 15, while the other terminal of winding 31 is connected to one group of correcting segments. It will be noted that there are two correcting segments for each sending segment and that they are divided into two groups made up of non-adjacent segments. One group is unconnected and is, therefore, dead, while the other group, as just described, is connected to one terminal of the winding 31 of correcting relay 30. The correcting relay 30 is provided with an armature 35 connected to a grounded source of energy 36 and coöperating with a contact 37.

Brushes 11 are driven to successively interconnect the receiving, correcting and sending segments with common rings by a phonic motor. This motor comprises a rotor 40 mounted upon a brush carrying shaft 41 and provided with a plurality of projecting teeth 42. Surrounding the circumference of rotor 40 are a plurality of operat-

ing electromagnetic windings grounded at one terminal and divided into a number of groups. In the motor shown, there are three groups of four windings each, but it is to be understood that the number of groups and the number of windings per group may be increased or decreased as the occasion requires and as desired. One group, which for the sake of convenience will be arbitrarily designated as the first group, is composed of windings 51, 52, 53 and 54. The second group is made up of the windings 61, 62, 63 and 64, while the third group is made up of windings 71, 72, 73 and 74.

Associated with these operating windings is a multiple switch 75 which is controlled, as will be hereinafter explained, by line current impulses to determine which of the hereinbefore mentioned groups of windings will be energized at any particular interval. Switch 75 comprises a plurality of pairs of cams 85, 86 and 87. Each cam is provided with as many projecting teeth as there are groups of energizing windings, in the present instance there being four such teeth, and all are connected to and rotated by a shaft 88. Shaft 88 is provided with a ratchet wheel 89 which is adapted to be engaged by a suitable holding pawl 90 and a stepping pawl 91. Stepping pawl 91 is operated by an electromagnet 92, one terminal of whose winding is connected by a conductor 93 to contact 37 of correcting relay 30. The other terminal of the winding of electromagnet 92 is grounded. One of the cams of each of the pairs 85, 86 and 87 is associated with a movable contact, all of which are connected together, and by a conductor 95 connected to a fixed contact 96 of a vibrating fork 97. The other cam of each pair is also provided with a movable contact, all of which are connected together, and by a conductor 98 joined to a fixed contact 99 of fork 97. These movable cam contacts are associated with fixed contacts which are connected to the various groups of energizing windings. Thus, the fixed contacts associated with cams 85 are connected to the first group of windings, the right-hand contact being connected to windings 51 and 52 of this group, and the left-hand contact being connected to windings 53 and 54 of this group. In the same manner, the fixed contacts of switches 86 and 87 are respectively connected to the second and third group of windings.

Fork 97 is connected to a grounded source of energy 100 and is provided with a movable contact 101 adapted to vibrate between contacts 96 and 99. It is also provided with the usual vibrator switch 102 and an operating electromagnet 103 whereby, when the fork is once set in motion, the vibration will continue in the well-known manner.

When the fork is vibrating, contacts 96 and 99 are alternately engaged by movable

contact 101, and consequently source 100 is alternately connected through conductors 95 and 98, and the contacts of cam 85 to windings 51 and 52, and 53 and 54 in pairs. An investigation of Fig. 2 will show that while some of the teeth 42 of rotor 40 may be directly in front of the poles of windings 51 and 52, others are offset from the poles of windings 53 and 54. This construction is common with phonic motors, and a detailed description of the operation is, therefore, unnecessary.

The source of power driving arm 6 of distributor 5 may be regulated to run slightly slower than rotor 40 is being driven by its operating windings, so that the normal tendency is for brushes 11 to move ahead of the brushes carried by arm 6. The signal current reversals imparted to line L traverse line relay 10 in the usual manner. If it be assumed that positive impulses cause armature 12 to engage contact 14 and negative impulses cause the armature to engage contact 15, each reversal of the line current from negative to positive will cause armature 12 to move from contact 15 to contact 14. The engagement of armature 12 and contact 14 will complete a circuit from grounded source 13 to the common receiving ring in the ordinary way. A circuit will also be completed from source 13 through resistance 16, and winding 18 of leak relay 20 to ground. The energization of winding 18 causes armature 25 to leave contact 26. Until this contact is broken, however there is a path prepared from source 13 through armature 12, contacts 14 and 26, and armature 25 to the common correcting ring. If, during this momentary supplying of current to the common correcting ring, the correcting brushes 11 are inter-connecting this ring with a dead segment, the circuit is not completed. If, however, brushes 11 have gained upon the brushes carried by arm 6, so that the reversal takes place when the correcting brushes are interconnecting one of the live segments with the common correcting ring, the circuit previously traced will be completed through winding 31 of correcting relay 30. The energization of winding 31 causes armature 35 to engage contact 37, and the circuit is completed from grounded source 36 through conductor 93 to correcting electromagnet 92. Electromagnet 92 thereupon causes pawl 91 to rotate shaft 88 so that the teeth of cams 85 disengage their movable contacts and the teeth of cams 86 engage their movable contacts. The energizing circuit from source 100 through contacts 96 and 99 of fork 97 has now been changed from the first group of windings to the second group of windings, and since, as will be noted from Fig. 2, this group is behind the first group as compared to the direction of rotation of rotor 40, the speed of this rotor

will be slightly decreased. The next reversal in line L, which under the conditions assumed will be from positive to negative, causes armature 12 to move from contact 14 to contact 15, which results in the energization of winding 19 of leak relay 20, and consequently, the withdrawal of armature 25 from contact 26.

A circuit is also completed from source 13 through armature 12 and contact 15, through winding 32 of correcting relay 30, the energization of which causes armature 35 to become disengaged from contact 37 and electromagnet 92 becomes deenergized, whereupon pawl 91 is retracted ready to engage the next tooth of ratchet wheel 89. If at the time of the next reversal, that is, from negative to positive, brushes 11 are still ahead of the brushes carried by arm 6 sufficiently to cause a live correcting segment to be interconnected with the common correcting ring, correcting electromagnet 92 will again become energized precisely in the manner hereinbefore described, and cam shaft 88 will be caused to rotate another step. This rotation of shaft 88 causes the teeth of cams 86 and 87 to transfer the energizing circuits, including source 100, from the second to the third group of windings, and rotor 40 is again slowed down. The next correction will remove the control of the energizing circuits from cams 87 to cams 85 and, since a complete cycle of the operating windings has been made, the first group, during this transition, will be behind the third group, and the speed of rotation of rotor 40 will be again decreased.

While in the system disclosed corrections are made only on reversals from negative to positive, it will be readily understood that by reversing the connections of line relay 10, corrections may be made on reversals from positive to negative. It will also be understood that the grouping of the operating windings may be reversed, and instead of a diminution in the speed of rotor 40 at each correction an acceleration may be provided if desired.

The invention claimed is:

1. A synchronizing system comprising two independently driven bodies, a transmission line operatively interconnecting said bodies, a motor for driving one of said bodies, and means controlled by current impulses over said line to shift the magnetic field of said motor to alter the speed thereof.

2. A synchronizing system comprising two independently movable bodies, a transmission line operatively interconnecting said bodies, a motor having a plurality of electromagnetic windings for driving one of said bodies, and a rotatory switch member controlled by current impulses over said line for controlling the energization of said windings to vary the speed of their motor.

3. A synchronizing system comprising a correcting current distributor, a corrected current distributor, a transmission line operatively interconnecting said distributors, a motor having a plurality of electromagnetic windings divided into groups for driving said corrected distributor, an energizing source for said windings, a multiple switch for associating the different groups of said windings with said source, and electromagnetic means controlled by current impulses imparted to said line from said correcting distributor to control the operation of said switch.

4. In a synchronizing apparatus, the combination of a plurality of electromagnetic windings divided into groups, means associated with said windings to convert electromagnetic energy into a rotary movement, a source of energizing current for said windings, a multiple switch controlling the circuit connections associated with said windings and said source for separately connecting any group of windings to said source, and an electromagnet for actuating said switch.

In witness whereof I hereunto subscribe my name this 18th day of May, A. D. 1915.

CHARLES E. SCRIBNER.
